J. M. CROWE

VALVE FOR PNEUMATIC TOOLS

Filed Mar. 22, 1919

Inventor—
John Marshall Crowe
By Walter P. Murray
Attorney.

UNITED STATES PATENT OFFICE.

JOHN MARSHALL CROWE, OF COVINGTON, KENTUCKY, ASSIGNOR OF ONE-HALF TO
LOUIS K. DE BUS, OF CINCINNATI, OHIO.

VALVE FOR PNEUMATIC TOOLS.

Application filed March 22, 1919. Serial No. 284,501.

To all whom it may concern:

Be it known that I, JOHN MARSHALL CROWE, a citizen of the United States of America, and a resident of Covington, in the 5 county of Kenton and State of Kentucky, have invented a new and useful Improvement in Valves for Pneumatic Tools, of which the following is a specification.

My invention relates to a valve for use 10 with a tool of the type described in United States patent to Ash, 1,195,897, which is adapted to be moved by hand to admit fluid under pressure alternately to opposite ends of a piston cylinder, to reciprocate the piston 15 therein with greater force in one direction than in the other.

The object of my invention is a valve which may be actuated quickly by a simple movement, which will not detract from the 20 pressure of the fluid admitted at one end, and has a simple means for lowering the force of the fluid admitted to the other end of the cylinder.

The object is attained by the means described in the specification, and illustrated 25 in the accompanying drawing, in which;

Fig. 1, is a front elevation of the head of a pneumatic tool provided with a valve embodying my invention.

Fig. 2, is a side elevation of the same.

Fig. 3, is a sectional view taken upon line 3—3 of Figure 2.

Fig. 4, is a sectional view taken upon line 4—4 of Figure 1.

Figs. 5 and 6, are views similar to Figure 4 with the valve in different positions.

Fig. 7 is a vertical section of the tool.

The housing A, of my valve forms the head of a pneumatic tool and is screw threaded to fit the piston cylinder B, thereof. The housing has a transverse tapered recess a, and a longitudinal central bore extending through it, the outer portion a¹, of which receives the admission pipe C, and the 45 lower portion a², of which leads into the piston cylinder B. In tools of this type the cylinder B has a port near its lower end as shown at 25 in the Ash patent, which construction is common and old in the art, and 50 therefore requires no illustration or further reference. Housing A, has likewise a transverse bore, one end of which receives the pipe

C¹, which connects with the end of the piston cylinder B, opposite the end in which the housing A is seated and the other end C², of 55 which constitutes an exhaust port.

Valve D, is tapered to fit the walls of recess a, and has an enlarged diametrical bore d, a bore d', of reduced diameter and a peripheral groove d², of reduced diameter 60 and located upon the side of the bore d, opposite the bore d'. Valve D, has a stem d³, upon one end of which a handle E, is secured and the opposite end of which passes through cap nut F, and receives a pin d⁴, which is 65 adapted to set in notches in the tension regulating block f. Between the cap nut F, and the valve D, and surrounding the valve stem is a coiled spring d⁵.

After the valve D, has been seated in its 70 recess and the cap nut F, has been adjusted, the parts are secured in fixed relation by passing a handle G, through the casing A, and in contact with a notch f', in the cap nut F. The handle G, therefore performs a 75 double function, that of holding the parts of the valve in their fixed relation, and of a handle by means of which the tool may be handled by the operator. Piston cylinder B may have near its lower end, ports through 80 which the air exhausts upon the forward movement of the piston. Such a port is shown at P, Fig. 7.

In operation by movement of the handle E, the operator brings the bore d, in alignment with the ends a', a², of the longitudinal bore in the housing A, as shown in Fig. 6, the fluid under pressure then has a direct and unimpeded passage to the piston cylinder and drives the piston therein with undiminished force to the opposite end of the cylinder. By a partial revolution of the handle E, the operator then moves the valve to a position wherein the reduced bore d', registers with the admission port a', and one end 95 of the bore d, registers with pipe C' (Fig. 5). This causes the groove d², to place the passage a² in communication with the exhaust port C². The reduced size of the bore d', and the tortuous passage through which 100 the fluid under pressure has to pass reduces the force of the fluid under pressure which is admitted to the opposite end of the piston cylinder. The reduced size of the groove d²,

likewise, impedes the escape of fluid from the piston cylinder, so that the piston is returned to the upper end of the piston cylinder with much less force than that with which it was 5 carried on its forward stroke.

The movement of the handle E, to put the opposite ends of the cylinder in communication with the fluid under pressure is through a small arc of a circle as is shown in Figs. 5 10 and 6. Hence this movement is one which an operator can make with great rapidity. This is advantageous in that it permits the operator to deliver several blows of the piston in a second.

15 When the valve is moved to the position shown in Fig. 6, the port in the cylinder wall, such as the port 25 in the cylinder shown by patentee Ash, permits the cylinder below the piston to exhaust on the power 20 stroke of the piston and permits the fluid under pressure to escape when the piston has reached the end of its power or down stroke, and when the valve is moved to the position shown in Fig. 5, the air under pressure starts 25 the piston on its return or upstroke and moves the piston upward beyond such port in the cylinder, whereupon part of the fluid under pressure entering the lower part of the cylinder, escapes thru the port in the 30 cylinder, while part of the fluid under pressure completes the return stroke.

Pin d^4 , limits the inward movement of valve D, against the tension of the spring d^5 , so that there is a space for the circulation of 35 oil which surrounds valve D, which seats in its recess sufficiently snugly to prevent the passage of air between it and the walls of the recess. The stem d^3 , journals at one end in casing A, and at the opposite end in cap 40 nut F. This construction takes the wear off of the valve D, to a large extent. However should the valve become worn allowance

may be made for the wear by removing the pin d^4 , unscrewing the block f , a step, and passing the pin d^4 , through the stem and 45 having it engage the next notch in the block f .

What I claim is:—

1. A valve for a pneumatic tool comprising 50 a housing having a transverse recess, a longitudinal bore and a transverse bore intercepted by the recess, and a valve seated in the recess and having an enlarged diametrical bore adapted to be brought into alignment with the longitudinal bore in the housing, a reduced bore leading into the diametrical bore at an acute angle, a reduced peripheral groove upon its side opposite the reduced bore, a transverse valve stem, and a handle mounted upon the valve stem.

2. A valve for a pneumatic tool comprising 55 a housing having a tapered transverse recess, a tapered valve seated in the recess and having a transverse valve stem extending through opposite sides of the housing, a cap nut surrounding one end of the valve 60 stem and closing the open end of the recess, a spring between the valve and the cap nut and surrounding the valve stem, an adjustable block upon the valve stem for regulating the position of the valve in the recess, 65 and a handle upon the opposite end of the valve stem, the housing and the valve having ways therein for admitting and distributing fluid under pressure through the valve.

3. A valve for pneumatic tools comprising 70 a housing, a transverse recess in the housing, a valve seated in the housing, a cap nut closing the recess and a handle passing through 75 the housing and engaging the cap nut and locking it against rotation.

In testimony whereof, I have hereunto 80 subscribed my name this day of March, 10, 1919.

JOHN MARSHALL CROWE.
